DESCRIPTION

FIG. 1 is a top perspective view of a first embodiment of an aircraft passenger compartment cover shown in an environment of use with an aircraft passenger compartment; FIG. 2 is a top perspective view of the first embodiment of the aircraft passenger compartment cover of FIG. 1 shown in an environment of use with the aircraft passenger compartment;

FIG. 3 is a top perspective view of the first embodiment of the aircraft passenger compartment cover;

FIG. 4 is a front elevation view of the first embodiment of the aircraft passenger compartment cover;

FIG. 5 is a rear elevation view of the first embodiment of the aircraft passenger compartment cover;

FIG. 6 is a side elevation view of the first embodiment of the aircraft passenger compartment cover;

FIG. 7 is a second side elevation view of the first embodiment of the aircraft passenger compartment cover;

FIG. 8 is a top plan view of the first embodiment of the aircraft passenger compartment cover;

FIG. 9 is a bottom plan view of the first embodiment of the aircraft passenger compartment cover;

FIG. 10 is a top perspective view of a second embodiment of the aircraft passenger compartment cover shown in an environment of use with the aircraft passenger compartment;

FIG. 11 is a top perspective view of the second embodiment of the aircraft passenger compartment cover of FIG. 10 shown in an environment of use with the aircraft passenger compartment;

FIG. 12 is a top perspective view of the second embodiment of the aircraft passenger compartment cover;

FIG. 13 is a front elevation view of the second embodiment of the aircraft passenger compartment cover;

FIG. 14 is a rear elevation view of the second embodiment of the aircraft passenger compartment cover;

(Continued)

FIG. 15 is a side elevation view of the second embodiment of the aircraft passenger compartment cover; FIG. 16 is a second side elevation view of the second embodiment of the aircraft passenger compartment cover; FIG. 17 is a top plan view of the second embodiment of the aircraft passenger compartment cover; and, FIG. 18 is a bottom plan view of the second embodiment of the aircraft passenger compartment cover. The dashed broken lines shown in FIGS. 9 and 18 depict portions of the aircraft passenger compartment cover that form no part of the claimed design. The additional dashed broken lines shown in FIGS. 1, 2, 10, and 11 depict environment structure only that form no part thereof.
